CURTAIN ROD

Allen B. Wilson, Evanston, Ill., assignor to Acme Steel Company, Chicago, Ill., a corporation of Illinois

Application December 20, 1943, Serial No. 514,904

2 Claims. (Cl. 211—105.1)

This invention relates to an improvement in curtain rods, and its purpose is to provide an improved curtain rod which will be strong and durable in use and which may be economically manufactured.

Heretofore, it has been the common practice to form curtain rods, upon which curtains, draperies and the like are supported, as solid metal members, made of materials such as steel, brass and the like, and, in order to obtain sufficient strength to support the weight of the objects suspended therefrom, it has been necessary to make these rods of substantial thickness, with the result that they have required the use of a considerable amount of metal and have been heavy and inconvenient to handle, in addition to having a relatively high initial cost.

The principal object of the present invention is to overcome the above-mentioned difficulties by providing an improved curtain rod comprising a metal tube having its interior chamber filled with fibreboard or other non-metallic material which is preferably highly compressed during the process of manufacture.

The nature of the invention will be understood from the following specification, taken with the accompanying drawing, in which one embodiment is illustrated. In the drawing,

Figure 1 shows a front elevation of a section of the improved rod mounted in supporting brackets;

Fig. 2 shows a plan view and an end elevation of a long strip of thin sheet metal which may be used in forming the outer tubular portion of the rod illustrated in Fig. 1;

Fig. 3 shows a plan view and an end elevation of a bar of fibreboard or other non-metallic material, which is adapted to be rolled up and compressed within the metal strip shown in Fig. 2, when this strip is curled into tubular form;

Fig. 4 shows a cross-sectional view through the metal strip shown in Fig. 2 and the non-metallic bar illustrated in Fig. 3, when these members have been partially curled into tubular form;

Fig. 5 is a sectional view similar to that of Fig. 4, illustrating the process of manufacture at a later stage of the curling operation, where the longitudinal edges of the metal strip have been partially overlapped;

Fig. 6 shows a transverse sectional view of the completed curtain rod after the curling operation has been completed; and

Fig. 7 is a perspective view of a section of the completed rod, showing a sectional view thereof

at one end, which illustrates the overlapping relationship of the longitudinal edges of the metal tube and the compressed character of the internal filling.

As illustrated in Fig. 1, the improved curtain rod 10 is mounted upon a pair of supporting brackets 11 which are secured to a wall or a window casing by screws 12. The rod 10 is adapted to support curtains, draperies or the like which are illustrated by dotted lines at 13, and the rod has sufficient strength to maintain it against lateral bending under the influence of the objects 13 which are suspended therefrom between the brackets 11.

This improved curtain rod is formed from a sheet metal strip 14 and a body of non-metallic material which may preferably be in the form of a bar 15 of fibreboard or other suitable non-metallic material which is preferably of a fibrous nature. The metal strip 14 may be comparatively thin, for example, about twenty-five thousandths of an inch (.025 in.) in thickness, and it may be formed of steel, brass or other material having sufficient ductility to permit it to be curled into tubular form and to retain its shape after it has been curled to compress within it the bar 15 of non-metallic material which is to constitute the interior filling of the metal tube.

In the process of manufacture, the non-metallic bar 15, which is of substantially lesser width than the metal strip 14, is placed upon the strip 14, with the longitudinal edges of the two members in parallel relationship, and the two members are then curled together about a longitudinal axis, as illustrated in Fig. 4. This curling operation is continued to bring the longitudinal edges 14a of the metal strip into overlapping relationship and to curl the bar 15 into annular form, in the manner illustrated in Fig. 5. The curling operation is then continued further, with a resulting further compression of the bar 15, until the final stage of the curling operation is reached, where it will be found that the longitudinal edge portions of the metal strip 14 overlap to a substantial degree and that the bar 15 has become compressed so that it assumes substantially the form and texture of a solid body of circular cross section enclosed within the metal tube, as illustrated in Figs. 6 and 7. By substantially overlapping the edges of the metal tube, as illustrated, and by using a metal strip having the required ductility and hardness, it will be found that the curled strip will retain its tubular form without fastening the overlapping parts together, notwithstanding the high degree of compression of

55

the non-metallic contents of the tube but, if desired, the overlapping edges of the strip which forms the metal tube may be welded, soldered or otherwise secured together.

By forming a curtain rod according to the improved method of the present invention, it will be found that a strong and durable supporting rod may be provided with the use of metal which is very thin and which would not of itself have the required strength and stiffness except for the provision of the internal compressed filling. It is therefore possible, by the use of this invention, to form curtain rods of attractive appearance with the use of a very small quantity of metal and with the use of other materials which are relatively inexpensive. Curtain rods which are satisfactory for some uses may be made according to the present invention by curling a thin metal strip and overlapping the longitudinal edges to a suitable degree without any connection of the overlapping parts and without any

filling of the internal chamber, but the use of an internal compressed filling, as described above, is preferable.

Although one form of the invention has been shown and described by way of illustration, it will be understood that it may be constructed in various other embodiments which come within the scope of the appended claims.

I claim:

10 1. A curtain rod comprising a thin metal strip curled into tubular form with its longitudinal edges overlapping and having a body of non-metallic material compressed therein.

15 2. A curtain rod comprising a thin metal strip curled into tubular form and having its longitudinal edges overlapped throughout a substantial part of the circumference of the tube, said edges being unattached, and a body of non-metallic material compressed in said tube.

20 ALLEN B. WILSON.
